UNITED STATES PATENT OFFICE.

STANISLAW J. LUKASZEWSKI, OF DETROIT, MICHIGAN.

ENGINE.

1,298,744.

Specification of Letters Patent. Patented Apr. 1, 1919.

Application filed April 11, 1918. Serial No. 227,862.

To all whom it may concern:

Be it known that I, STANISLAW J. LUKASZEWSKI, a citizen of the United States, and residing at Detroit, in the county of Wayne 5 and State of Michigan, have invented a new and Improved Engine, of which the following is a specification.

This invention relates to means for preventing the circulating liquid of internal 10 combustion engines from freezing, and its object is to provide a heater for this circulating liquid which will form a portion of the engine structure and which will be provided with a burner that is so located as to 15 keep fluid the lubricant within the crank case of the engine.

This invention consists, in combination with the cylinders of a multi-cylinder internal combustion engine which are arranged in 20 two groups, of a heater positioned between the two groups of cylinders, the structure being such that the water jacket of the cylinders constitutes a portion of the heater. It also consists in providing a heating coil 25 through which the circulating liquid will pass from a source of supply, preferably the radiator, to the upper portion of the water-jacket of the engine, preferably to the manifold connecting the water-jacket to the upper portion of the radiator. It further consists in combination of the details of construction illustrated in the accompanying 30 drawings and particularly pointed out in the claims.

In the accompanying drawings, Figure 1 35 is a side elevation of an engine embodying this improved heater. Fig. 2 is a view on the opposite side of the engine, a portion of the walls of the crank-case and of the cylinders being broken away. Fig. 3 is a vertical section on the line 3—3 of Fig. 2.

Similar reference characters refer to like parts throughout the several views.

In my prior Patent No. 1,007,710, dated 45 November 7, 1911, I have shown a device for heating the circulating water of the engine so as to prevent it from freezing during extreme weather. A pipe leads from the radiator to a heating coil and from the heating coil to the water-jacket of the cylinder. No provision, however, is made for heating the lower part of the crank case and the lubricating oil which is usually stored therein; where engines are designed to lubricate the 50 moving parts by splashing up the oil in the crank-case by means of the connecting rods,

it is necessary that this lubricant shall always be fluid. There is also in this prior construction a great loss of heat because the heating mechanism is entirely separate and 60 apart from the rest of the construction and in the path of the air rushing in through the radiator. In the present device, however, I have embodied the heater in the engine itself midway between two groups of 65 the cylinders, so that all the heat will be utilized to heat the cylinders and the circulating water of the engine. The lower part of the device which embodies the burner extends down so low that the contents of the 70 crank case will be heated thereby.

Referring now to the drawings, the cylinders 4 are connected to the upper portion 5 of the crank case, the lower portion 6 of the crank case being attached to the upper in any 75 desired manner. Extending longitudinally of the cylinders is a water-jacket 7 and a manifold 8 to conduct the circulating water to the radiator 9, which is shown in dotted lines in Figs. 1 and 2. The crank shaft 12 is longer between the cranks 13 and 14 than the usual type of engines because of the distance occupied by the heater, and a long bearing 15 may be provided at this point.

The heater may be of any desired construction, but I prefer to have it of the general design in my prior Patent No. 1,249,644, dated December 11, 1917. Circulating water is conducted to the lower ends of the coils 16 and 17 by the pipe 10 and rises in these 80 coils as it is heated and flows through the connection 22 and pipes 23 and 24 to the manifold 8. As it flows around through the water jackets of the cylinders it cools and finally passes to the radiator through the 95 pipe 18. The pipe 10 connects to the lowest liquid supply point of the circulating system, which is the bottom of the radiator in the drawings but may be the bottom of the water pump or of the pipes thereof.

The inner portion 26 of the shell of the heater is generally cylindrical and is spaced apart from the side wall 27 of the water jackets of the cylinders sufficiently to permit free circulation between the water jackets. A partition 28 parallel to the wall 27 is similarly spaced from the part 26 and the space between them again connects to the water jackets. A door 29 closes an opening in the flat portion 29 of the main cylinder 105 block and supports the burner 30. A curved shield 31 extends outward from the shell 110

over the U shaped mixing tube 32 of this burner.

An air chamber 33 between the cylinder walls and the longitudinal walls 28 and 34 5 connects to the space within the shell below the cowl 35 of the heater by means of a passage 36. An air passage 37 extends across between the side walls of the engine block and its upper wall has perforations 38, above 10 which is a baffle plate 39 which directs the air away from the burner. Should an excessive pressure of air develop at either end of the passage 37 and at the perforations 38, the small baffle 41 will prevent the air 15 from rushing to the burner, all excess of pressure being relieved by the passage 36.

As the shell of this heater and its double bottom or air passage 37 extend down into the crank-case of the engine, the lubricant 20 therein becomes warm soon after the burner is lighted and therefore will be splashed up to the desired places at the starting of the engine. This avoids the danger of cutting the cam shaft and pistons because of the lack 25 of lubricants between the working surfaces.

I claim:—

1. In an internal combustion engine, the combination of two groups of cylinders longitudinally separated, a crank case on which 30 the cylinders are mounted, a heating coil mounted between the two groups of cylinders, a burner beneath the coil and a shell inclosing the coil, said shell comprising two thicknesses with a water space between them 35 so as to constitute a part of the heating system of the engine.

2. In an internal combustion engine, the combination of two groups of cylinders longitudinally separated, a crank-case on which 40 the cylinders are mounted, a heating coil mounted between the two groups of cylinders, a burner beneath the coil and a shell inclosing the coil, said shell comprising two thicknesses with a water space between connecting to the water-jacket of the engine, 45

and passages to convey air to the burner having their ends at the side walls of the upper portion of the crank-case.

3. In an internal combustion engine, the combination of two groups of cylinders longitudinally separated, a crank-case on which the cylinders are mounted, a heating coil mounted between the two groups of cylinders, a burner beneath the coil and a shell inclosing the coil, said shell comprising two thicknesses with a water space between them so as to constitute a part of the cooling system of the engine, a crank-shaft and a bearing 50 55 therefor below said burner.

4. In an internal combustion engine, the combination of two groups of cylinders longitudinally separated, a crank-case on which the cylinders are mounted, a heating coil mounted between the two groups of cylinders, a burner beneath the coil and a shell 60 65 inclosing the coil, said shell comprising two thicknesses with a water space between constituting a part of the cooling system of the engine, and a passage to convey air to the burner having its ends at the side walls of 70 the upper portion of the crank-case, the upper wall of the air passage being perforated, and baffle plates positioned between the walls of the cylinder adjacent the heater to regulate the flow of air to said burner. 75

5. In an internal combustion engine, the combination of two cylinders separated longitudinally of the crank shaft, a crank-case on which the cylinders are mounted, a heating coil mounted between the cylinders, a burner beneath the coil, and a case for the burner extending down into the crank-case. 80

6. In an internal combustion engine, the combination of the crank case and a cylinder mounted thereon, a heater adjacent to 85 said cylinder and extending down into the crank case, and a water jacket for the cylinder extending adjacent the shell of the heater.

STANISLAW J. LUKASZEWSKI.
